SPACERS FOR STEEL INSERTS IN REINFORCED CONCRETE**Fritz Spatz and Werner Spatz, both of 14 Mulfkestrasse, Schwerte, Germany****Filed June 19, 1956, Ser. No. 592,428****Claims priority, application Germany Sept. 14, 1955****5 Claims. (Cl. 50—507)**

This invention relates to a spacer for steel inserts in reinforced concrete serving to maintain the required distances from the outside, and to a method for its production.

It is an object of the invention to provide a cheap spacer which is easy to handle and permits subsequent lifting or displacement of the steel inserts without being dislocated or tilting over.

Another object of the invention is to provide a spacer with a substantially punctiform support.

With these objects in view, the spacer according to the present invention consists of a perforated and preferably slotted disc which is provided with waves or corrugations. This disc-shaped spacer can be put on the structural steel netting or on single rods already on the fitting yard and ensures a tight clamping fit which permits also its attachment on vertical inserts.

The corrugations provided on the discs have the advantage that the disc is made very resisting thereby. First of all, however, they ensure a satisfactory, tight seat of the disc on the steel insert, so that it is held thereon in a position at right angles to the rod. Owing to the spring action of the spacer it is possible to fit the disc on round bracing and reinforcing irons of various dimensions, e.g. of 6-8 mms. diameter. By using a material of high elasticity, moreover, it is ensured that the spacer reassumes its original position at right angles to the round iron if it should be depressed by inadvertence.

The spacers according to the invention are produced either from a metal sheet and simultaneously provided with the corrugations, or from a strip corresponding to the width of the ring, bent into a ring and corrugated simultaneously or prior thereto, e.g. by means of corresponding profiled rollers or the like.

Of late double-rod armourings have been increasingly adopted. In this type of armouring the interconnected rods are disposed parallel to each other and are arranged in known manner. In order to adapt the disc to such a double-rod armouring, according to the present invention it takes the form of a perforated and corrugated disc having a sector-shaped cut-out. In this way it is possible to fit the spacer on one of the discs while the second rod comes to lie in the sector-shaped cutout. The next spacer can be fitted on the second rod, being turned through 180° about the axis of its hole, while the first rod in this case comes to lie in the circular sector-shaped cutout.

Owing to the sector-shaped formation of the cutout it is ensured that the armouring rod fitted with the spacer is seized by the inner circumference of the ring with an angle of grip ensuring a sufficient clamping fit of the spacer on the rod. Thus the rod is prevented from slipping out of the central hole or of the sector-shaped cutout of the disc and hence the spacer is secured against being lifted off.

Each edge of the circular sector-shaped sector is preferably arranged on the crest of a wave, whereby the

2

cutout can be provided in the disc in a simple manner.

In the accompanying drawings two preferred embodiments of the invention are shown by way of illustration and not by way of limitation.

- 5 Fig. 1 is a plan view of a ring embodying the invention,
Fig. 2 is a cross section on line II—II of Fig. 1,
Fig. 3 is a plan view showing a modification thereof,
Fig. 4 is a side view as per arrow IV in Fig. 3, omitting
the steel rods, and

- 10 Fig. 5 is a plan view showing a spacer in the course
of production.

Similar reference numerals denote similar parts.

- Referring to the drawing in greater detail, it will be
seen that the spacer consists of a disc 1 of a material
15 of high elasticity, preferably of sheet steel which can
be hardened. In the center thereof there is a hole 3
whose diameter corresponds to the outer diameter of the
round steel serving for the reinforcing. As already men-
20 tioned, the hole may be of such a size that the disc
owing to its elasticity can be engaged on rods of different
diameters.

- Furthermore, the disc is provided with radial corrugations 4 flattening towards its outer edge. Thus the
25 highest waves are around the hole 3, so that a very good
seat of the disc on the round steel is ensured. In order
to facilitate the operation of placing the disc on the
armouring rod, it is preferably split or provided with a
radial slot 2, Fig. 1.

- In the embodiment as per Figs. 3 and 4, which is in-
30 tended for double-rod armourings, the spacer consists
of a disc 1 having a central perforation and radially di-
rected corrugations 4 flattening in an outward direction
and formed with a circular sector-shaped cutout defined
35 by edges 7 and 8 forming an angle of 90° with each
other. One of the two parallelly arranged armouring
rods 9 is received in the central hole 3 of the disc while
the second rod 10 is accommodated in the sector-shaped
40 cutout between the edges 7 and 8 each of which is pref-
erably arranged on the crest of a wave or corrugation 4.
The walls of the form from which the bars 9 and 10
are to be spaced are indicated at 11 and 12.

- A preferred method of producing the spacers is shown
in Fig. 5. A straight strip of steel, preferably of a width
45 of 10 mms., and a thickness of, say, 0.3 mm., is first
corrugated, for instance, by passing the strip between
two intermeshing toothed wheels spaced from each other
by a clearance which corresponds at least to the thick-
50 ness of the steel strip, then bent around a mandrel so
as to form an annular disc, whereby the corrugations
will be flattened in the outer part of the disc and in-
creased in depth in the inner part thereof, and then cut
off at 6. By way of alternative, the spacers may be
punched and drawn out of sheet steel.

- The depth of the corrugations preferably should be at
55 least 6 mms., and advantageously 7 or 8 of such waves
will be provided.

- While the invention has been described in detail with
respect to certain now preferred examples and embodi-
60 ments of the invention it will be understood by those
skilled in the art after understanding the invention that
various changes and modifications may be made without
departing from the spirit and scope of the invention and
it is intended, therefore, to cover all such changes and
65 modifications in the appended claims.

- More particularly, our novel retainer, although specifi-
cally adapted as a spacer and locator for reinforced
concrete, having the advantage of being fixedly seated
on a steel rod over which it is slipped, may also be used
70 for other purposes where such spacing and/or locating
and such a fixed seat may be required, and it may be
made of an elastic material other than steel, so as to

suit the particular purpose or manner for which it is to be used.

I claim:

1. A spacer for accurately spacing reinforcement rods from form members in concrete structures, consisting of an arcuate member of substantially annular shape forming a central opening through which a reinforcement rod is adapted to pass in holding engagement with said spacer, said arcuate member being corrugated so as to resiliently adapt itself to rods of different diameter and having alternating radially extending ridges and hollows arcuate in cross-section and forming along the circumference of said central opening axially extending edges adapted to engage said rod in axial direction thereof so as to form an axially extending support for said spacer preventing tilting thereof relatively to said rod.

2. A spacer for accurately spacing reinforcement rods from form members in concrete structures, consisting of an arcuate member of substantially annular shape forming a central opening through which a reinforcement rod is adapted to pass in holding engagement with said spacer, said arcuate member being corrugated so as to resiliently adapt itself to rods of different diameter and having alternating radially extending ridges and hollows arcuate in cross-section and increasing in depth from the periphery towards said central opening and forming along the circumference of said central opening axially extending edges adapted to engage said rod in axial direction thereof so as to form an axially extending support for said spacer preventing tilting thereof relatively to said rod.

3. A spacer for accurately spacing reinforcement rods from form members in concrete structures, consisting of an arcuate member of substantially annular shape forming a central opening through which a reinforcement rod is adapted to pass in holding engagement with said spacer, said arcuate member being corrugated so as to resiliently adapt itself to rods of different diameter and having alternating radially extending ridges and hollows arcuate in cross-section and increasing in depth from the periphery towards said central opening and forming along the circumference of said central opening axially extending edges adapted to engage said rod, in axial direction thereof so as to form an axially extending support for said spacer preventing tilting thereof relatively to said rod, said arcuate member being split in radial direction forming radial edges spaced from each other a distance less than the diameter of said central opening.

4. A spacer for accurately spacing reinforcement rods from form members in concrete structures, consisting of

an arcuate member of substantially annular shape forming a central opening through which a reinforcement rod is adapted to pass in holding engagement with said spacer, said arcuate member being constructed so as to facilitate

5 said arcuate member being corrugated so as to resiliently
adapt itself to rods of different diameter and having alternating radially extending ridges and hollows arcuate in cross-section and increasing in depth from the periphery towards said central opening and forming along the circumference of said central opening axially extending edges
10 adapted to engage said rod in axial direction thereof so as to form an axially extending support for said spacer preventing tilting thereof relatively to said rod, said arcuate member being split by a sector-shaped cutout forming substantially radial edges including an angle of up
15 to 90°.

5. A spacer for accurately spacing reinforcement rods from form members in concrete structures, consisting of an arcuate member of substantially annular shape forming a central opening through which a reinforcement rod
20 is adapted to pass in holding engagement with said spacer, said arcuate member being corrugated so as to resiliently adapt itself to rods of different diameter and having alternating radially extending ridges and hollows arcuate in cross-section and increasing in depth from the
25 periphery towards said central opening and forming along the circumference of said central opening axially extending edges adapted to engage said rod in axial direction thereof so as to form an axially extending support for said spacer preventing tilting thereof relatively to said
30 rod, said arcuate member being split by a sector-shaped cutout forming substantially radial edges including an angle of up to 90°, each of said radial edges extending along the crest line of one of said ridges.
